UNITED STATES PATENT OFFICE.

CHARLES MILLS, OF NEWTON, MASSACHUSETTS, ASSIGNOR, BY MESNE ASSIGNMENTS,
TO SACO-PETTEE COMPANY, OF NEWTON, MASSACHUSETTS, A CORPORATION OF
MASSACHUSETTS.

MACHINE FOR ATTACHING CLOTHING TO FLATS.

1,029,452.

Specification of Letters Patent. Patented June 11, 1912.

Application filed November 12, 1909. Serial No. 527,644.

To all whom it may concern:

Be it known that I, CHARLES MILLS, of Newton, in the county of Middlesex and State of Massachusetts, a citizen of the 5 United States, have invented a new and useful Improvement in Machines for Attaching Clothing to Flats, of which the following is a specification.

The attaching of clothing to flats has been 10 accomplished by machinery which is large, expensive to build, and not easily portable, so that it usually forms part of the machine builder's plant. As a result when it is necessary to replace the clothing on flats 15 they must be sent from the mill to the builder.

My invention comprises a simplified machine which is comparatively small, is quite portable, may be constructed at comparatively 20 small expense, and is fitted to be part of the equipment of any mill in which flats are used. Moreover it is easily operated so that by means of it the clothing on flats may be replaced by any good mechanic. In 25 the drawings the preferred embodiment of my machine is shown.

Figure 1 is a side elevation of a portion of a machine embodying my invention. Fig. 2 is a cross section on line 2—2 of Fig. 1, 30 showing the machine in position to begin its operations. Fig. 3 is a similar section showing the jaws in the act of attaching the clothing. Fig. 4 is a longitudinal section on line 4—4 of Fig. 2, and Fig. 5 is a plan, 35 the jaws being open, the machine being ready to receive the work.

It will be understood that the machine in question may be made of any desired length according to the length of the flats and that 40 certain of the parts shown will be as long as are necessary, the cams and other operating parts being duplicated along the machine as occasion may require. Upon the base A are mounted uprights B at convenient distances apart, such as to give the necessary support to the moving parts.

C is a cam shaft which is supported in suitable bearings b in the uprights B. This shaft runs the length of the machine and is 50 rotated by power applied through a pulley or gear (not shown) or by hand through a crank handle, as may seem best. Keyed to this shaft (see Figs. 2 and 3) are two cam D, E, which are set opposite to each

other, the same key preferably serving both 55 cams. They have hubs of sufficient width to fill the space between the bearings b to two successive uprights. Against these cams lie the lower ends of levers D¹, E¹, which are pivoted for oscillatory movement 60 upon the fulcrum studs D², E². These studs also run the length of the machine and the bearing D³, E³ of each lever is sufficiently wide to lie between the bearings b¹ of the adjacent uprights B so as to prevent lateral 65 play.

The upper arm of each lever is comparatively short and each carries a jaw d, e, these jaws being sufficiently long to form with the next jaws in line a continuous attaching mechanism (see Fig. 5 where the middle jaw is shown in full and fragments of the adjacent jaws are also shown). Each jaw d, e has a substantially rectangular groove in its lower front edge, the working 70 surfaces or dies of which are indicated at d¹, d², e¹, e², the exact shape of the groove depending somewhat upon the shape of the edge of the flat with which it is to coöperate. The face d³, e³ of each jaw projects forward 75 sufficiently to coöperate in the attaching operation by pushing the outer portion of the metallic edge of the clothing down toward the surface of the flat as the jaw moves toward the flat, thus stretching the clothing 80 and drawing it around the edge of the flat until the groove reaches a clamping position to clamp the clothing against the flat.

The flat is lettered F and the fasteners or metallic edges of the clothing f. G is the 85 table mounted on the uprights B on which the clothing and flat are supported during the covering operation. For this purpose the table is provided with a longitudinal recess g of sufficient width and depth to allow 90 the teeth f' of the clothing to hang down into it. The rim g¹ at each side of the recess is sufficiently wide and strong to furnish a firm support for the flat and clothing during the covering operation. The 95 table thus coöperates with the jaws in applying the clothing.

The operation of this machine is simple. The clothing is laid on the table G with its teeth f' projecting into the recess g. It is 100 properly centered and the flat F laid upon it, the metallic edges f of the clothing standing upright as shown in Fig. 2. The shaft

C is then turned and moves the cams D, E from their position in Fig. 2 to the position in Fig. 3. This action separates the lower ends of the levers D¹, E¹ and brings the jaws 5 d, e toward each other, so that the faces d³, e³ of the jaws engage the edges f of the clothing, stretching said clothing and turning said edges over the corners of the flat. Thereafter the edges f are clamped against 10 the flat by the jaw faces d', e', and finally the edges are given a final squeeze by the dies d¹, d², e¹, e², as shown in Fig. 3 to set the same. The cams then release the levers and they fall back to their first position because of their shape and weight. The cams 15 are set opposite each other and are preferably keyed together as well as to the cam shaft, and the dies are set in the same position the entire length of the machine so as to 20 act simultaneously upon the clothing.

The simplicity of this machine is apparent and it is evident that the dies may be differently shaped according to the shape of the surface of the flat which they are to 25 engage and may be differently mounted and operated if thought best. The embodiment of the invention shown however has proved satisfactory both from the point of view of construction and that of operation. The 30 moving parts are well supported and the construction lends itself to the setting up of machines of different lengths with but slight changes.

What I claim as my invention is:

35 1. In a machine for attaching clothing to flats, in combination, a frame, a table carried thereby, a pair of jaws one pivotally mounted on each side of said table, and means for causing said jaws to approach a flat located 40 on said table to attach clothing thereto, each jaw having a face adapted to engage the upright edge of a fastener and turn it against the horizontal surface of the flat and having

a die adapted thereafter to engage said turned edge and clamp it against said flat. 45

2. In a machine for attaching clothing to flats, in combination, a frame, a table carried thereby and adapted to support a flat and its clothing, a pair of jaws one pivotally mounted on each side of said table, and means for causing them to approach said flat simultaneously, each jaw having a face opposing the face of the other jaw and having below said face and adjacent to it a right angled die, whereby as said jaws approach the unattached clothing on a flat, said clothing having fasteners attached to each edge thereof, the face of each jaw will engage said fasteners simultaneously and press them toward each other and against 50 said flat thereby stretching said clothing about said flat and said dies will simultaneously clamp said fasteners about said flat, as set forth.

3. A machine for attaching clothing to 55 flats, comprising a frame, a table carried thereby to support the flat, a pair of jaws on each side of the table, and means for causing said jaws to approach and stretch the clothing on said flat and thereafter to clamp a 60 fastener on each edge of said clothing to said flat and set the same.

4. A machine for attaching clothing to 65 flats, comprising a frame, a table attached thereto, a pair of jaws on each side of the 70 table, said jaws having fastening-turning and clothing-stretching surfaces, and means for causing said jaws to approach and stretch said clothing and thereafter to attach one or more fasteners connected thereto 75 to said flat, whereby the stretched clothing is attached to said flat as set forth. 80
